VENTILATOR FOR WATER CLOSET

Charles J. Majauskas, Chicago, Ill.

Application December 21, 1953, Serial No. 399,309

4 Claims. (Cl. 4—213)

This invention relates to ventilators for water closets and is an improvement on the apparatus disclosed in my Patent No. 2,639,440, issued May 26, 1953.

My prior patent discloses a system for ventilating a water closet, the functioning of which is initiated when the seat ring is forced down and the closet is put in use. Recognizing, however, that it is often desirable and convenient to also close the cover and use the closet bowl as a seat, my present invention provides a means for rendering the ventilating system inoperative when both the seat ring and cover are forced down to the seat position.

The main objects of this invention, therefore, are to provide an improved ventilator for water closets, the functioning of which is initiated at the time the closet is put in use and the functioning of which is prevented when the cover is also lowered and the closet is used as a seat, and to provide an improved attractive form of arrangement of a seat mounting for housing the switches for controlling the operation of the ventilator.

In the particular embodiment of this invention, shown in the accompanying drawings:

Fig. 1 is a side elevation of this improved water closet ventilator shown mounted on a wall adjacent and connected to a water closet bowl and flush tank;

Fig. 2 is an enlarged cross-sectional detail of the safety valve fitting adapted for interposition in the flush water pipe and which prevents a surge of the flushing water from reaching to the blower;

Fig. 3 is a perspective view of the valve member for the same removed from the fitting;

Fig. 4 is a section through the ventilator housing taken on the plane of the line 4—4 of Fig. 1, showing in elevation the motor-driven blower and the solenoid operated vent valve;

Fig. 5 is a transverse sectional elevation of the same, taken on the line 5—5 of Fig. 4;

Fig. 6 is an enlarged cross-sectional elevation of the seat and cover hinge mountings, as viewed from the plane of the line 6—6 of Fig. 1;

Fig. 7 is a plan view of the seat and cover hinge mountings;

Fig. 8 is an enlarged side elevation of the same, taken on the line 8—8 of Fig. 7; and

Fig. 9 is an enlarged cross-sectional detail of the mounting post including the switching mechanism of the present invention, as taken on the plane of the line 9—9 of Fig. 7.

An improved water closet ventilator constructed in accordance with this invention comprises the ventilator unit 7, a safety valve fitting 8, and a seat and cover controlled switch means 9, designed for attachment and operation to effect the ventilation of a water closet bowl 10 to the conventional vent stack 11 at the time the closet is put into use.

The ventilator unit 7 comprises a housing 12 wherein is mounted a blower 13, driven by a motor 14, and a vent valve fitting 15, the valve 16 of which is actuated by a solenoid 17.

2

The housing 12, as herein shown, is of rectangular form. Its open top permits the insertion and appropriate location of the parts just described. A hood 18 telescopes with the vertical walls of the main part of the housing 12 to form a closure for the open top thereof. The housing is provided with suitably placed apertures through which fastening means may be inserted for attaching the unit to a wall 69.

The blower 13, preferably of the impeller type, is directly mounted on the motor 14, which is supported on a base spaced above the bottom of the housing 12. The blower 13 has its exhaust 20 extending exteriorly of the housing 12 for connection with the vent stack 11.

The motor 14 is a conventional, fractional, horsepower motor adapted for small units of this kind. It has associated therewith a condenser 21 interposed between the wires 22 to a source of electrical power and the wires 23 to the switch mechanism 9. The wires 23 enter the housing 12 through a section of conduit secured to the housing 12 by a fastening means 23.1.

The vent valve fitting 15 is directly connected to the intake 24 of the blower 13 and has a nipple 25 extending exteriorly of the housing 12 which is connected to the safety valve fitting 8 by a pipe 26. The valve 16 is arranged for vertical movement in the fitting 15 so that gravity normally urges the valve head 27 to rest on the seat 28 thereby closing communication between the bowl 10 and the vent stack 11 when the motor 14 is idle.

The solenoid 17 is located in the housing 12 below the valve fitting 15, and is energized concurrently with the blower motor 14 to open valve 16. Its armature 29 is connected to a bell crank lever 30 pivoted at 31 and attached to a stem 32 of the valve 16.

The safety valve fitting 8 is of a construction substantially such as shown in Patent No. 2,449,134. This fitting is approximately T-shaped with a main part 33 and a stem part 34. The main part 33 is threaded so that it may be conveniently inserted in the flush water pipe 35 which leads from a source of water to the flush water inlet 36 for the closet bowl 10. This source of flush water may be either a tank 37 such as shown in Figure 1, or it may be a valve-controlled water pressure source, such as is commonly used for water closets, particularly in large buildings and institutions.

The valve 38 comprises a disk-shaped cap part 39 and a lever 40 secured in axially spaced relationship on opposite sides of a hinge pin 41. The hinge pin 41 mounts the valve 38 so that the cap part 39 is disposed to close the end of the port 42 in the fitting stem port 34 and locates the lever 40 in the main part 33. A suitable gasket 39.1 is secured to the cap 39 to seal the port 42. A weight 43 on the back of the cap part 39 normally holds the valve 38 with the cap part 39 retracted from the port 42, whereby communication is normally open from the closet bowl 10 through the port 42, the connecting pipe 26 and the vent valve fitting 15. The lever 40 is so shaped and dimensioned that when the closet is flushed the surge of water through the fitting 33 will cause the lever 40 to shift the cap 39 to close the port 42, preventing any back-flow of water up through the pipe 26 into the fitting 15 from whence the water might reach the mechanism in the housing 12. The stem part 34 of the fitting 8 has an inspection port 44 in which is secured a threaded plug 45 (see Fig. 1).

The switch means 9 comprises a pair of posts 46 and 47, a pair of cover hinge brackets 71 and 72 telescoped over the shaft 49, and a pair of seat hinge brackets 48 connected at the ends of a shaft 49, supported in bearings 50 offset from the respective posts 46 and 47.

The posts 46 and 47, are similar, except that one is right-hand and the other is left hand, as most clearly shown in Fig. 6. Each is provided with a chambered

hub part 51 offset from a channelled stem 52. The stems 52 have a downward extending portion 53 with threads 54 whereby the posts may be secured on the rim 55 of the bowl 10 by nuts 56.

A plunger 57 having an integral pin 58 is mounted in each of the chambered hub parts of posts 46 and 47, with plunger pin 58 extending exteriorly parallel to the post stem 52. A spring 59 is compressed against each plunger 57 by a threaded plug 60 so that the plunger pin 58 is normally depressed. The seat brackets 48 are attached to the rear underside of a seat 62. Tongues 61 on these brackets normally contact the plunger pins 58 so as to dispose the seat 62 at a slight angle to the top of the bowl 10. The construction can, of course, be such as to allow tongue 61 to break contact with plunger 58 and permit the seat 62 to be raised to a vertical position.

Each of the posts 46 and 47 is closed at its upper end by a threaded cap 63. Within one of these caps, which as herein shown is for post 46, is an insulating block 64 mounting a pair of electrical contacts 65 and 66 which are adapted to be closed by a switch arm 67 actuated by a switch pin 68 adjustably supported on the plunger 57.

The other post 47 is modified somewhat as is best shown in Figs. 7, 8, and 9. Within the cap 63 of the post 47 is an insulating block 73 mounting a pair of normally closed electrical contacts 74 and 75 which are adapted to be opened by a pivotally and resiliently mounted switch arm 76 actuated by a hard rubber switch pin 77 that is controlled by the position of the cover 84. The switch pin is guided within a vertical channel 81 formed in the post 47.

The channel 81 communicates with a cavity 79 formed in the post 47. The cavity 79 is adapted to receive the smaller end of a cylindrical plug 78. The plug 78 is formed with a central bore 80 which extends from the smaller end of the plug to a pocket 82 formed adjacent the outer or larger end of the plug. One end of a camming bar 93 fits within the bore 80 and is received in the pocket 82 while the other end supports the switch pin 77.

As previously mentioned, the cover 84 is attached by means of a pair of cover hinge brackets 71 and 72. One on these brackets, shown at 72 in the present arrangement, includes a rearwardly extending arm 85 that is adapted to fit within a transverse slot 86 formed in the bottom surface of the cylindrical plug 78. When the cover 84 is down, the arm 85 bears against the camming bar 83 and causes it to pivot about the pocket 82, thereby forcing the switch pin 77 upwardly. When the cover is raised, the camming bar is no longer acted on by the arm 85 and thus permits the switch pin to slide downwardly.

The wire 23 leads up through the channelled stem 52 of the post 47 to the normally closed contacts 74 and 75 and then leads up through the corresponding stem 52 of the post 46 to the normally open contacts 65 and 66, thus placing the two sets of contacts in series.

This improved ventilator unit 7 may be conveniently secured at any suitable point on the wall 69, more or less out of the way from a water closet bowl 10, flushing water for which is supplied from a tank 37, as herein shown, or from a valve-controlled water pressure line. Or, on occasion, the ventilating unit could be associated with an overhead flushing water tank. Mounting the housing on the wall 69, of course, will necessitate cutting a hole through the wall 69 to permit the exhaust 20 of the blower 13 to be connected to the usual vent stack 11. Also, it will require the cutting of a hole sufficient to provide for the wires 22 leading to a source of electricity.

The safety valve fitting 8 would be interposed in the flush water pipe 35 and connected to the nipple 25 of the valve fitting 15 by the pipe 26. The pipe 26 preferably would be of brass or copper so that it could be bent to the desired shape, to span these connections. Each end would be connected to these respective parts by the usual slip nut.

It will be seen from the foregoing description that the operation is as follows. When only the seat 62 is depressed it causes the tongue 61 of bracket 48 to raise plunger pin 58 against the action of spring 59. Switch pin 68 will force up switch arm 67 closing electrical contacts 65 and 66 energizing solenoid 17 and motor 14 of blower 13.

Upon energizing solenoid 17, armature 29 will actuate lever 30 opening valve 16. Valve 38, between the flush water pipe 35 and ventilating unit 7, will be opened due to gravity acting on weight 43 and the lack of flushing water in the flush water pipe 35. This completes an open circuit for evacuating gases from water closet bowl 10 into vent pipe 11 through the flush water pipe 35, through valve 38, through pipe 26, through valve 16, through blower 13, into vent pipe 11.

When the flushing water enters pipe 35, valve 38 will be closed due to the action of the flushing water on lever 49, thus cutting off the open circuit and preventing water from entering the ventilating unit. When seat 62 is released, spring 59 opens the electrical contacts 65 and 66 by retracting switch pin 68 and raises seat 62 at an angle by causing plunger pin 58 to bear on tongue 61.

When both the cover 84 and the seat 62 are depressed, the electrical contacts 65 and 66 will close in the same manner as previously stated but the rearwardly extending arm 85 of bracket 72 will cause the camming bar 83 to pivot upwardly about the pocket 82 to raise the switch pin 77. The switch pin 77 will force switch arm 76 to open the normally closed contacts 74 and 75.

Since these contacts are in series with the contacts 65 and 66, they will prevent the energizing of solenoid 17 and motor 14 of blower 13. Thus it is seen that the arrangement of the present invention provides a ventilating system for a closet bowl which functions when the seat is lowered and the closet is put in use but which is rendered inoperative when both the seat and the cover are lowered and the closet is used as a support. Useless operation of the ventilating system and the resultant wear and tear on the equipment are thereby eliminated.

Variations and modifications in the details of the structure and arrangement of the parts may be resorted to within the spirit and coverage of the appended claims.

I claim:

1. The combination of a water closet bowl having a seat and a cover, an electrically operated ventilator, a control circuit for said ventilator, a pair of posts mounted on said bowl and having chambered hub parts off-set from channelled stems extending through a rim portion of said bowl, plungers within said hub having pins extending downwardly below said hubs, seat hinges pivotally secured to said posts, tongues on said hinges normally contacting the lower ends of said pins, springs disposed within said hubs and urging said pins downwardly to partially raise the bowl seat, an insulating block mounting a pair of spaced electrical contacts and disposed within the upper part of the hub of one of said posts, an insulating member carried by said plunger in said one post and adapted to close said contacts when said seat is depressed against the action of said springs, an insulating block mounting a pair of normally closed electrical contacts and disposed within the upper part of the hub of the said other post, said other post being formed with a cavity and a vertical channel connecting said cavity and said upper part of the hub of said other post, a switch pin disposed in said channel and adapted to be forced upwardly to open said normally closed contact, a plug adapted to be inserted in said cavity, said plug having a central bore extending from the said cavity to a pocket formed adjacent the outer end of said plug, a camming bar adapted to seat in said pocket and extending into said cavity to engage said switch pin, means carried by one of said cover hinges for causing said camming bar to pivot about said pocket and force said switch pin upwardly when said cover is depressed, and wires extending through the channelled stems of said posts.

to connect said sets of electrical contacts in series in said control circuit.

2. The combination of a water closet bowl having a seat and a cover, an electrically operated ventilator, a control circuit for said ventilator, a pair of posts mounted on said bowl and having chambered hub parts offset from channeled stems extending through a rim portion of said bowl, plungers within said hubs having pins extending downwardly below said hubs, seat hinges pivotally secured to said posts, tongues on said hinges normally contacting the lower ends of said pins, springs disposed within said hubs and urging said pins downwardly to partially raise the bowl seat, and insulating block mounting a pair of spaced electrical contacts and disposed within the upper part of the hub of one of said posts, an insulating member carried by said plunger in said one post and adapted to close said contacts when said seat is depressed against the action of said springs, an insulating block mounting a pair of normally closed electrical contacts and disposed within the upper part of the hub of the said other post, said other post being formed with a cavity and a vertical channel connecting said cavity and said upper part of the hub of said other post, a switch pin disposed in said channel and adapted to be forced upwardly to open said normally closed contact, pin actuating means adapted to be inserted in said cavity, means carried by one of said cover hinges adapted to engage said actuating means and force said switch pin upwardly when said cover is depressed, and wires extending through the channeled stems of said posts to connect said sets of electrical contacts in series in said control circuit.

3. The combination of a water closet bowl having a seat and a cover, an electrically operated ventilator, a control circuit for said ventilator, a pair of posts mounted on said bowl and having chambered hub parts offset from channeled stems extending through a rim portion of said bowl, plungers within said hubs having pins extending downwardly below said hubs, seat hinges pivotally secured to said posts, tongues on said hinges normally contacting the lower ends of said pins, springs disposed within said hubs and urging said pins downwardly to partially raise the bowl seat, an insulating block mounting a pair of spaced electrical contacts and disposed within the upper part of the hub of one of said posts, an insulating member carried by said plunger in said one post and adapted to close said contacts when said seat is depressed against the action of said springs, an insulating block mounting a pair of normally closed electrical contacts and

disposed within the upper part of the hub of the said other post, said other post being formed with a cavity and a vertical channel connecting said cavity and said upper part of the hub of said other post, switch actuating means disposed in said channel and adapted to open said normally closed contact, first means mounted in said cavity and adapted to control said switch actuating means, second means carried by one of said cover hinges adapted to engage said first means to cause said switch actuating means to open said normally closed contact when said cover is depressed, and wires extending through the channeled stems of said posts to connect said sets of electrical contacts in series in said control circuit.

4. The combination of a water closet bowl having a seat and a cover, an electrically operated ventilator, a control circuit for said ventilator, a pair of posts mounted on said bowl and having chambered hub parts offset from channeled stems extending through a rim portion of said bowl, seat and cover hinges pivotally secured to said posts, a normally open switch in said circuit, said switch being mounted in one of said chambered posts and being adapted to close said circuit and actuate said ventilator when said seat is lowered, an insulating block mounting a pair of normally closed electrical contacts and disposed within the upper part of the hub of the said other post, said other post being formed with a cavity and a vertical channel connecting said cavity and said upper part of the hub of said other post, a switch pin disposed in said channel and adapted to be forced upwardly to open said normally closed contact, a plug adapted to be inserted in said cavity, said plug having a central bore extending from the said cavity to a pocket formed adjacent the outer end of said plug, a camming bar adapted to seat in said pocket and extending into said cavity to engage said switch pin, means carried by one of said cover hinges for causing said camming bar to pivot about said pocket and force said switch pin upwardly when said cover is depressed, and wires extending through the channeled stems of said posts to connect said sets of electrical contacts in series in said control circuit.
